(57) **CLAIM**

The ornamental design for a recessed flat hidden socket, as shown and described.

DESCRIPTION

FIG. 1 is a front perspective view of a recessed flat hidden socket, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view, shown in a closed configuration, thereof; and,

FIG. 10 is an exploded top perspective view, shown in an open configuration, thereof.

The broken lines in the drawings illustrate the portions of the recessed flat hidden socket, which form no part of the claimed design.

1 Claim, 10 Drawing Sheets
